(57) **CLAIM**

I claim the ornamental design for a punch device, as shown and described.

DESCRIPTION

FIG. 1 is a perspective view of an ornamental punch device showing my new design;

FIG. 2 is a right side view of the ornamental punch device as shown in FIG. 1;

FIG. 3 is a left side view of the ornamental punch device as shown in FIG. 1;

FIG. 4 is a top view of the ornamental punch device as shown in FIG. 1;

FIG. 5 is a rear view of the ornamental punch device as shown in FIG. 1; and,

FIG. 6 is a front view of the ornamental punch device as shown in FIG. 1.

The lines of contour shown in FIG. 1-6 are only for denoting surface curvature of the ornamental punch device, and do not constitute a part of the claimed design in any other manner.
